Duke Tatum INVENTOR
BY Victor J. Evans

WITNESS: *John D. Moran*

ATTORNEY

UNITED STATES PATENT OFFICE.

DUKE TATUM, OF DOTHAN, ALABAMA.

RAILWAY SWITCH.

Application filed November 14, 1925. Serial No. 69,123.

The object of the invention is to provide means for automatically throwing a switch when car carried devices of a particular type are thrown to operative position.

5 A further object is to provide electrically operated car carried means for controlling pilot wheels.

A further object is to provide a track structure including devices for engagement by either pilot wheel, said devices controlling a plurality of pivoted elements freely mounted with reference to each other and interengaging as described below, for throwing the switch point to the position required 15 for following the straight track or for rounding a curve or the like.

A still further object is to provide retaining means for the switch point.

With the foregoing and other objects in view, the invention consists in the novel construction and arrangement of elements described, illustrated and claimed, it being understood that modifications may be made within the scope of the claims without departing from the spirit of the invention.

In the drawing forming part of this application,

Figure 1 shows the track structure in top plan.

30 Figure 2 is a longitudinal section, the section being on the line 2—2 of Figure 1.

Figure 3 shows the car carried means in side elevation, with a portion of a car truck and wheel, in dotted lines.

35 Figure 4 shows the car carried devices in front elevation.

Figure 5 is a diagrammatic view of the circuit for controlling the magnets by which the respective pilot wheels are operated.

40 The straight rails of a track are designated 10 and 11, these rails being mounted on ties 12, and the rail 11 merging into deflected rail 13, for a curve, siding, or the like, and rail 13' being complementary to the rail 13.

45 On one of the ties 12, I pivot at 14 a pair of bars 15 and 16 having their forward ends pivoted at 17 to a transverse bar 18 extending perpendicularly with reference to the rails 10 and 11.

50 A lever 20 is fulcrumed at 21 on one of the ties, and is pivotally connected at 22 with the bar 18 and is operated thereby when one of the pilot wheels, referred to below, engages the bar 15 or 16 and throws one

of the bars outwardly with reference to the adjacent track rail.

The lever 20 has a tapered end portion terminating in a point 24, and the latter engages a V-shaped cutaway portion 25' in a 60 pivoted arm 25. This arm last named has a tapered end, the point of the arm engaging the cutaway portion 26 in switch point lever 27, pivoted at 28, on one of the ties.

The lever 28 is connected by means of 65 pivoted link 29 with switch point 30 and operates the latter in an obvious manner, the movement of this element being limited by short rail or stop 31.

In order to retain switch point 30 in the 70 position in which it is thrown, I provide a retaining or locking device designated 35 and provided with a slot 36 through which bolt 37 passes into one of the ties 12. One end of member 35 is tapered as shown at 75 35' and this end engages a V-shaped cutaway portion 38 in the end of element 27, the other end of element 35 having a bore 39 therein for the reception of one end of a coiled spring 40, the opposite end of the 80 spring being received by socket 41 in pivoted socket member 42. The expansion spring 40 imparts end thrust to element 35 and tends to hold switch point lever 27 in the position in which it is placed. 85

The car carried devices include levers or arms 50 and 51 pivotally mounted at their upper ends, these elements being downwardly deflected at 50' and 51' and mounting brackets 52, and supporting in connection with these brackets, axial members 53. Pilot wheels 54 are mounted on elements 53 and each includes a flanged portion 54', the latter engaging the edge of the track rail, at the head thereof, and being adapted to 90 engage pivoted bar 15 or 16, as the case may be.

The levers 50 and 51 are normally held in an upper and inoperative position by means of springs such as 55, but arms 50 100 and 51 are thrown to operative position by vertically movable bars 56 having upper offset ends 57 constituting armatures for co-operation with the magnets 58.

Upon the energization of the proper magnet, when the motorman, or engineer throws the switch in the required direction, (this switch being shown in Figure 5,) the pilot wheel for moving the track mechanism in the desired direction for controlling the 105 110

switch point 30, will be operated, and the switch point will be retained in that position by means of the retaining element 35.

In Figure 5, the electric switch 60, constituting a controlling device for determining the direction of travel of the car, cooperates with switch points 61 and 62, and has connection by means of wire 63 with battery 64. The other terminal of the battery is connected with wire 65, the latter leading to one of the magnets 58, and a wire 65' leading to the other magnet 58 which is in electrical connection by means of a wire 66 with contact point 62.

15 What is claimed is:—

1. The combination with a switch point, of a switch point operating lever, a pivoted arm freely engaging said lever and controlling the movement thereof, a pivoted lever 20 freely engaging the pivoted arm, said arm having detached endwise engagement with the levers and means adapted for operation by a car carried device, for controlling the lever.

25 2. The combination with a switch point, of a switch point operating lever, having recesses in opposite ends thereof, a locking device engaging one of said recesses, and a pivoted arm freely engaging the other recess 30 and controlling the movement of the switch point lever.

3. The combination with a switch point,

of a switch point operating lever, having recesses in opposite ends thereof, a locking device engaging one of said recesses, and a 35 pivoted arm freely engaging the other recess and controlling the movement of the switch point lever, and a spring for imparting end thrust to the locking device.

4. The combination with a switch point, 40 of operating means therefor including a plurality of levers pivotally mounted in spaced relation, and in alinement, a pivoted arm mounted between approaching ends of the levers, and freely engaging said ends, 45 one of the levers having operative connection with the arm, and said arm having operative connection with the other lever.

5. The combination with a switch point, 50 of operating means therefor including a plurality of levers pivotally mounted in spaced relation, and in alinement, a pivoted arm mounted between approaching ends of the levers, and freely engaging said ends, 55 one of the levers having operative connection with the arm, said arm having operative connection with the other lever, a locking device in alinement, at times, with one of the levers and freely engaging that lever, and a spring for imparting end thrust to 60 the locking device.

In testimony whereof I affix my signature.

DUKE TATUM.
